UNITED STATES PATENT OFFICE.

GEORGES HALTER, OF PARIS, FRANCE.

PASSAGE FOR PLANES TRAVELING AT PROGRESSIVELY-VARYING SPEEDS.

Application filed June 12, 1923. Serial No. 645,002.

To all whom it may concern:

Be it known that I, GEORGES HALTER, citizen of the Republic of France, residing in Paris, France, have invented certain new and useful Improvements in Passages for Planes Traveling at Progressively-Varying Speeds, of which the following is a specification.

My invention relates to a special arrangement of passages or tunnels used for apparatus conveying passengers from one place to another at speeds which are progressively accelerated either positively or negatively and wherein each change of speed produces an appreciable thrust which is due to the force of inertia occasioned by the weight of the body, this being applied at the center of gravity of the persons and tending to overthrow them rearwardly in the case of platforms which are progressively accelerated, or forwardly in the case of platforms which are progressively slowed up.

The said invention has for its object to induce the passengers to automatically displace their center of gravity forwardly or rearwardly and contrary to the said thrust, whereby the latter shall be annulled. For this purpose, the lines which in the known passages are either vertical, horizontal or parallel with respect to the transporting apparatus, for instance the lines represented by moldings, joints in brickwork, edges of posters or of the vaulting, and the like, are no longer disposed in the vertical and horizontal direction or parallel with the plane of the transporting arrangement, but are inclined to said directions, the direction and amount of the inclination depending upon the direction and value of the acceleration of speed in any given part of the passage, in such manner that the passengers will have an optical illusion causing them to imagine that they are proceeding upon an upwardly or downwardly inclined plane, and will thus be led to incline the body towards the top of this imaginary plane, or in the proper manner to equilibrate the effect of inertia which is due to the acceleration.

The appended drawings which are given by way of example illustrate embodiments of my invention.

Fig. 1 is a longitudinal section of a passage containing a horizontal platform traveling at a progressively increasing speed.

Fig. 2 is a transverse section of said passage.

Fig. 3 is a longitudinal section of a passage containing a horizontal platform traveling at a progressively decreasing speed. 60

In Fig. 1, 1 indicates the horizontal plane of the platform of a transporting apparatus composed of elements whereby persons are transported upon said platform from left to right at increasing speeds. According to 65 my invention, the lines 4, 5 upon the vertical walls of the tunnel 2 and 3, such as borders of moldings or joints of construction, edges of posters or of the vaulting 5 which are commonly horizontal, are herein 70 inclined downwardly in the direction of travel of the passengers, and the angle of inclination α of these lines is made greater in proportion to the degree of acceleration to which the passengers are subjected. In 75 like manner, upon the said walls 2 and 3, the lines 7 and 8 such as borders of moldings, joints of construction, edges of posters and the like which are usually vertical, are herein 80 made perpendicular to the above-mentioned lines 4, 5, 6, so that in the passage thus arranged, the passengers by reason of the optical illusion thus produced will imagine that they are traveling upon a plane which is upwardly inclined from left 85 to right of the figure, and will be thus induced to incline the body towards the top of this imaginary plane.

In Fig. 3, 9 indicates the horizontal plane of the platform of a transporting apparatus 90 composed of elements whereby persons are transported from left to right at decreasing speeds. According to my invention, the lines 10, 11 upon the vertical walls of the said tunnel, such as borders of moldings or 95 joints of construction, edges of posters or of the vaulting 12 which are commonly horizontal, are inclined upwardly in the direction of travel of the passengers, and the angle of inclination β of these lines is made 100 greater in proportion to the degree of acceleration to which the passengers are subjected, and in like manner, in the said tunnel the lines 13 and 14 such as borders of 105 moldings, joints of construction, edges of posters or the like which are usually vertical are made perpendicular to the above-mentioned lines 10, 11, 12, so that in the passage thus arranged the passengers by reason of 110 the optical illusion thus produced will im-

agine that they are traveling upon a plane which is downwardly inclined from left to right of the figure, and will be therefore induced to incline their bodies towards the top of this imaginary plane.

Obviously, the principles above set forth are applicable to constructions in which the planes of the transporter 1 and 9 are not horizontal.

10 I declare that what I claim is:

1. A tunnel containing an apparatus for transporting passengers at accelerated speeds, wherein the visible lines appearing upon the sides of the tunnel are inclined to

15 the direction of travel of said apparatus by an angle whose direction and magnitude depend upon the direction and value of the acceleration of speed, so that the passengers transported by said apparatus shall be given

20 an optical illusion inducing them to automatically displace their center of gravity towards the top of the imaginary plane resulting from the said optical illusion.

25 2. A tunnel containing an apparatus for transporting passengers at accelerated speeds, wherein the vaulting of the tunnel is inclined to the direction of travel of said

apparatus by an angle whose direction and magnitude depend upon the direction and value of the acceleration of speed, so that the passengers transported by said apparatus shall be given an optical illusion inducing them to automatically displace their center of gravity towards the top of the imaginary plane resulting from the said 35 optical illusion.

3. A tunnel containing an apparatus for transporting passengers at accelerated speeds, wherein the vaulting of the tunnel and the visible lines appearing upon the 40 sides of the tunnel are inclined to the direction of travel of said apparatus by an angle whose direction and magnitude depend upon the direction and value of the acceleration of speed, so that the passengers transported by said apparatus shall be given an optical illusion inducing them to automatically displace their center of gravity towards the top of the imaginary plane resulting from the said optical illusion. 45

In witness whereof I have hereunto set my hand.

GEORGES HALTER.
